UNITED STATES PATENT OFFICE.

ALFRED Z. BAKER, OF NEWARK, NEW JERSEY, ASSIGNOR TO FULTON SPECIALTY CO., A CORPORATION OF NEW JERSEY.

DESIGN FOR A CHART FOR EDUCATIONAL GAMES.

Application filed May 18, 1921. Serial No. 470,613. Term of patent 14 years.

To all whom it may concern:

Be it known that I, ALFRED Z. BAKER, a citizen of the United States, residing at Newark, in the county of Essex and States of New Jersey, have invented a new, original, and ornamental Design for a Chart for Educational Games, of which the following is a specification, reference being had to the accompanying drawing, forming a part thereof.

The invention is clearly illustrated in the

accompanying drawing which shows my new, original and ornamental design for a chart for educational games.

I claim:

The ornamental design for a chart for educational games, as shown.

Dated April 27th, 1921.

ALFRED Z. BAKER.
